ALEXANDER WALKER REID, OF STRATFORD, NEW ZEALAND.

MILKING-MACHINE PULSATORE.

1,150,452.

Specification of Letters Patent. Patented Aug. 17, 1915.

Application filed October 14, 1914. Serial No. 866,590.

To all whom it may concern:

Be it known that I, ALEXANDER WALKER REID, subject of the King of Great Britain, residing at Stratford, New Zealand, have invented a new and useful Improved Milking-Machine Pulsator; and I do hereby declare the following to be a full, clear, and exact description of the same.

This invention relates to an improved construction of milking machine pulsator for use in alternately connecting various parts of the machinery, and particularly the teat cups, with air and with a source of vacuum.

The invention relates especially to that class of pulsator that is made automatic in its action through the agency of atmospheric air pressure caused by the connection of portions of the pulsator with vacuum, and in which a pair of cylinders are arranged in tandem and each provided with a piston mounted therein, both of which pistons are attached to a slide valve that is adapted to be moved across a set of three ports by means of which a central vacuum port may be alternately brought into connection with each side port while the other is uncovered, and in which such reciprocation of the slide valve is brought about by alternately connecting the outer ends of the two cylinders with air and with the vacuum source, reversely to one another by the movements of the slide valve.

The invention consists in improved means whereby these alternate connections of the cylinder ends with air and with vacuum may be brought about in a simple and positive manner, and especially whereby the change over in the connections shall be made quickly at the end of the piston's movements in each direction.

In fully describing the invention reference will be made to the accompanying sheet of drawings, in which:

Figure 1 is a plan, and Fig. 2 a front elevation of the complete pulsator. Fig. 3 is a plan of the slide block showing the various ports therein. Fig. 4 is an underneath plan of the two slide valves used in this invention and placed in their operative positions relative to one another. Fig. 5 is a sectional elevation taken on the line 5-5 of Fig. 3. Fig. 6 is a cross section taken on the line 6-6 of Fig. 3. Fig. 7 is an alternative detail that will be afterward more fully referred to.

A, A' are the two cylinders that are

mounted in the same axial line on the reverse ends of the slide block B. Each cylinder is provided with a piston C from which piston rods C' extend to the slide valve D, 60 being attached thereto in the manner shown in the drawings that is by means of cross pins c on their ends engaging within notches or depressions d on the slide valve. This manner of connection allows of the piston 65 rods being raised to free the slide valve, whenever desired, so that the pistons and slide valve may be removed for attention or repairs of any kind. Each cylinder is closed at its outer end and is opened at its inner 70 end and the pistons and piston rods are so adjusted that in their movements, when one piston is at the outer end of its cylinder, the other will be at the inner end of its cylinder.

The slide block B is provided with a set of 75 three main ports arranged in a row thereon and the central one E of which is connected with the source of vacuum through a pipe connection E'. The outer ports F and F' are connected respectively with pipes G and 80 G' that lead to the teat cups or other appliances to be pulsated. The slide valve D at one limit of its movement is adapted to connect the central port E with the outer port on that side and to uncover the other 85 outer port so that the reciprocation of the slide valve, will in the usual way, alternately connect the pipe F and F' with the vacuum source and with air, so as to obtain the desired pulsations. The slide block 90 is also formed with a second set of three ports arranged parallel to the main port. The central port H of this set is arranged in connection with the central port E of the main ports, through the bore H' (Fig. 6), 95 the passage through such bore into the port being controlled by a needle valve J. The two outer ports K and K' are connected to the respective outer ends of the cylinders A and A' on the reverse sides of the slide 100 block as shown by the dotted lines in Fig. 3, through the small tubes M, M', that is the port K is connected to the cylinder A' and the port K' to the cylinder A. A second slide valve N is provided to reciprocate over 105 these ports and in its movements, at one end to connect the central port H (and through it the vacuum) with the outer port K and thereby connect the cylinder A' with the vacuum, and at the same time to uncover the 110 outer port K' and allow air to enter the cylinder A. These are the positions shown in

the drawings, so that the air pressure upon the piston of the cylinder A is ready to act against the vacuum in the cylinder A' and force both pistons and the main slide valve D across to the reverse position. At the other limit of movement, the slide valve N uncovers the port K and connects the port K' with vacuum, so that the relative connections of the two cylinders A and A' with 5 vacuum and air are altered and the pistons and slide valve D caused to move back again. These movements of the slide valve N are obtained by the special means shown and are adapted to be made quickly and positively as the pistons and main slide valve 10 reach their limits of movement in each direction. These means consist of the tappet arms O and O' extending horizontally from the respective ends of the main slide valve D 15 and situated one on each side of the slide valve N, but with a distance between them sufficient to allow for almost the full travel of the main slide valve without affecting the slide valve N. Each tappet carries a cylinder P extending longitudinally with the machine, and in each cylinder a helical spring R is inserted the outer end of which 20 engages the adjacent side of the slide valve N. This slide valve is therefore held between the tappets and the spring cushions 25 thus provided.

The slide valve N is held from any movement during the major portion of the main slide valve's travel in each direction, by 30 means of a suitable spring detent, that will not give way under the force exerted by the compression of the springs R, caused by the travel of the main slide valve but which will give way when engaged by the tappet itself 35 and then allow the spring that has been compressed, to force the slide valve over quickly to its other position, where it will be again retained until the slide valve moves to its limit in the reverse direction. The 40 means shown in Figs. 1 and 2 for effecting these purposes consist of a spring arm S that is attached to the frame and overlies the slide valve N and is provided with a tooth s on its underside. This tooth 45 engages a round knob or projection n extending across the top of the slide valve and prevents the slide valve moving to either side until the pressure of the main slide valve is exerted upon it, when the spring S will be 50 forced upward and the knob n slide underneath the tooth s, the slide valve being then quickly pushed over by the expansion of the spring R. The tooth s will then drop down and engage the other side of the knob. An 55 adjusting screw S' is provided for regulating the tension of the spring S.

Stop T are arranged upon the slide block B to engage the slide valve N at each limit of its movement and to prevent this slide 60 valve from being pushed too far under the

action of the springs R, or projections n' (Fig. 1) may be made on the ends of the slide valve between which and the knob n the tooth s will drop and thereby lock the slide valve from further movement. 70

Alternative means for retaining the slide valve N and for releasing it under pressure may be employed, for instance those shown in Fig. 7 may be used. In these means, the knob n of the slide valve is engaged by a 75 metal ball U that projects from the bottom end of a cylinder U' mounted vertically upon the slide block. The ball is kept normally down by the compression of a spring S^a contained within the cylinder and the 80 compression of which is governed by the set screw S^b threaded through the closed top end of the cylinder. The rate of operation of the pulsator is governed by means of the 85 needle valve J which regulates the rate of the exhaustion of air from the cylinder ends through the pipes M and M', the ports K and K' and the port H and bore H'.

What I do claim as my invention, and desire to secure by Letters Patent is:— 90

1. In a milking machine pulsator the combination with a slide block formed with a series of three main ports therein, a pair of cylinders mounted one at each end of such slide block, pistons mounted within such cylinders having piston rods extending through the inner ends of the cylinders, a slide valve attached to such pistons and adapted in its reciprocation to connect the central port with each of the outer ports in turn while uncovering the other outer port, a second series of three ports arranged in the slide block, the central one of which is connected with the central main port, while the outer one on each side is connected with the outer end of the cylinder on the reverse side of the central port, and a second slide valve adapted to move across these latter ports and in its reciprocations to connect the central port with each of the outer ports in turn, while uncovering the other outer port, of tappet arms extending from the two ends of the main slide valve and passing one on each side of the second slide valve, spring 100 cushions extending between the respective tappet arms and the said slide valve and yielding means whereby such slide valve may be prevented from movement until engaged by the tappet arms of the main slide valve, substantially as specified. 105

2. In a milking machine pulsator having a pair of cylinders, pulsation pipes, a source of vacuum, double pistons mounted within the cylinders, a main slide valve operated by the double pistons and adapted alternately to connect the pulsation pipes with air and the source of vacuum, means for bringing the pistons alternately and reversely under the action of the vacuum, said means comprising a part having a series of 110

- three ports, the central one of which is connected permanently with the source of vacuum while the other one on each side is connected with one of the cylinders, a second 5 slide valve mounted to move across such ports and in its reciprocations to connect the central port with each of the outer ports in turn while uncovering the other outer port, a tappet arm extending from each end of the 10 main slide valve and passing across the corresponding side of the second slide valve, spring cushions extending between the respective tappet arms and the said slide valve, and yielding means for holding such 15 slide valve from movement, substantially as specified.
3. In a milking machine pulsator, a main slide valve for causing the pulsations and a secondary slide valve for governing the 20 movements of the main slide valve, tappet arms upon the respective ends of the main slide valve and extending on the respective sides of such secondary slide valve, spring cushions in compression between both tappet 25 arms and the slide valve between, and means whereby the said slide valve may be held from movement until engaged by the

tappet arms of the main slide valve and may then be released and pushed across by the expansion of the cushion spring compressed by the independent travel of the main slide valve, substantially as specified. 30

4. In a milking machine pulsator, a main slide valve for causing the pulsations, and a secondary slide valve for governing the 35 movements of the main slide valve, tappet arms upon the respective ends of the main slide valve and extending across the respective sides of the secondary slide valve, spring cushions in compression between both tappet 40 arms and the slide valve between, a spring detent bearing upon the top of said secondary slide valve and a knob or projection upon the top of said valve with which such spring detent engages, substantially as specified. 45

In testimony whereof, I have signed this specification in the presence of two subscribing witnesses.

ALEXANDER WALKER REID.
